CLOTHES DRYER OR SIMILAR ARTICLE

Lawrence R. Collins, Jefferson County, Ky., assignor to
General Electric Company, a corporation of New York

Filed Mar. 22, 1963, Ser. No. 74,083

Term of patent 14 years

(Cl. D49—1)

FIG. 1

FIG.3

FIG.2

FIGURE 1 is a fragmentary front perspective view of a clothes dryer embodying my new design;

FIGURE 2 is a cross-sectional view thereof taken on the lines 2—2 of FIGURE 1 in the direction of the arrows; and

FIGURE 3 is a side elevational view thereof.

The broken lines representative of the lower portion of the clothes dryer have been omitted in FIGURE 1 for convenience of illustration.

The front, the back, and the side not shown of the clothes dryer shown are substantially plain. The dominant features of my design for the clothes dryer disclosed

reside in the portions shown in full lines.

I claim:

The ornamental design for a clothes dryer or similar article, substantially as shown and described.
